UNITED STATES PATENT OFFICE

2,586,003

DUCK HUNTER'S DRAG

John D. Caslor, St. Vital, Manitoba, Canada

Application April 7, 1949, Serial No. 86,027

5 Claims. (Cl. 43—1)

1

My invention relates to new and useful improvements in duck hunters' drags, an object of my invention being to provide a device of the character herewithin described whereby shot ducks and the like falling into water can be retrieved from an adjoining piece of land without the necessity for boats or excessive wading.

A further object of my invention is to provide a device of the character herewithin described which is capable of being launched by hand and retrieved for further use.

A still further object of my invention is to provide a device of the character herewithin described which is capable of being directed while floating on the water in order to engage the shot bird.

Another object of my invention is to provide a device of the character herewithin described which is readily carried, simple in operation, and otherwise well suited to the purpose for which it is designed.

With the foregoing objects in view, and such other objects and advantages as will become apparent to those skilled in the art to which this invention relates as this specification proceeds, my invention consists essentially in the arrangement and construction of parts such as will hereinafter be described, reference being had to the accompanying drawings in which:

Figure 1 is a top plan view of my device in the launching or folded position.

Figure 2 is a perspective view of my device in the floating or open position.

Figure 3 is a perspective fragmentary view of one end of the wing-bar showing an alternative means for opening same.

In the drawings like characters of reference indicate corresponding parts in the different figures.

During the hunting season many birds after being shot fall into bodies of water nearby, necessitating either extensive wading or the use of a boat in order to recover same. Due to the nature of the terrain normally associated with duck hunting and the like it is extremely difficult to obtain boating facilities and wading is restricted considerably as often the depth of the water increases rapidly upon leaving the shore line.

Consequently many birds are lost during the season which is a matter of aggravation to the majority of hunters. The present invention relates to means whereby a bird falling in water may be recovered from the shore, limitations as to the radius of action of the device being governed by the throwing capacity of the operator.

Proceeding now to describe my invention in detail, it will be seen upon reference to the accompanying drawings that my device comprises a centre-bar 1 of elongated rectangular con-

2

figuration manufactured preferably from wood or hollow metal or plastic possessing floatation characteristics. The nose end 2 of the centre-bar 1 is notched as at 3 and carries a pair of wing-bars 4 hingedly secured at the ends 5 thereof on each side of the centre-bar 1 by means of the hinges 6.

The wing-bars 4, manufactured from similar material to the centre-bar 1 are also elongated rectangular members and are held normally, in the embodiment depicted in Figures 1 and 2, in what I define as spring-spread position or open V-formation as clearly shown in Figure 2. This position is accomplished by means of a coil-type spring 7 secured to the wing-bars 4 on the outer faces 8 thereof and extending around the nose 2 of the centre-bar 1 being positioned within the notch 3 therein. The position of the hinges 6 with relation to the wing-bars 4 causes the ends 5 thereof to engage with the sides 9 of the centre-bar 1 when said wing-bars are extended, the angular relationship of the wing-bars to the centre-bar being governed by the inclined end faces 10 of the wing-bars 4.

In order that the wing-bars 4 may be held in parallel closed relationship to the centre-bar 1 during carrying and launching, I have provided a locking means collectively designated 11 including a casing 12 of box formation secured to the end 13 of the centre-bar 1. A shot-bolt 14 in the form of a pin engages with a suitable aperture within the end plate 15 of the casing 12 and extends through supporting plate 16 into an open-ended notch or aperture 17 formed within the end 13 of the centre-bar 1. A coil-spring 18 surrounding a portion of the pin 14 reacts between the inner face of the end-plate 15 and a washer 19 welded to the pin thus effecting an endwise bias to the pin 14 in the direction of the notch 17.

Bolt receivers 19, consisting of angulated brackets, are attached to the outer ends 20 of the wing-bars 4 and are apertured as at 21 to receive the operating end 22 of the shot-bolt 14. Reference to Figure 1 of the accompanying drawings will show that when the wing-bars are folded parallel to the centre-bar 1 the bolt receivers 19 lie within the notched portion 17 of the centre-bar 1, in overlapping relationship, the portion 22 of the bolt 14 passing through the aperture 21.

An anchor cord 22 extends from the outer end of the shot-bolt 14 and comprises a convenient length of cord or line the opposite end of which is anchored to the shore or otherwise secured by the operator. In this connection a heavy-duty fishing line has been found to be preferable, some hundred feet being a convenient length for normal operation.

In operation the wing-bars 4 are folded par-

allel with the centre-bar 1 and the end 22 of the shot-bolt 14 is engaged within the apertures 21 of the bolt-receivers 19. In this position it will be appreciated that the aforementioned coil-type spring is under tension exerting an outward bias to the wing-bars 4. When a bird falls into the water the operator launches the device in the manner of a javelin causing the device to fall substantially beyond the bird and if possible in alignment therewith. The opposite end of the anchoring cord 23, which is held by the operator upon the shore, is pulled sharply, the inertia of the device, which is floating upon the water, enabling the shot-bolt 14 to be withdrawn momentarily against the pressure of spring 17'. As soon as the portion 22 of the shot-bolt 14 disengages with the apertures 21 within the bolt receivers 19, the aforementioned spring 7 causes the wing-bars to take up the position shown in Figure 2 of the accompanying drawings.

The device is then pulled slowly towards the shore, the bird engaging within the acute angle formed between either of the wing-bars and the centre-bar, whereupon it may be drawn to shore.

If the device has landed out of alignment with the bird, then by walking to the left or right the operator can cause engagement of the bird within aforesaid acute angle.

Figure 3 of the accompanying drawings shows an alternative method of causing the wing-bars to take up the open V-formation in which case the spring 7 is not required. A drag-paddle 24 is secured to the outer ends 20 of the wing-bars consisting of a planar paddle inclining outwardly from the wing-bar as clearly shown in the drawing. The locking means 11 hereinbefore described is similar in construction and operation, a bolt receiver 25 being provided as in the previous embodiment.

In operation, the device is launched as hereinbefore described, whereupon the shot-bolt 14 is withdrawn and the device pulled towards the operator. Paddles 24 engage with the water and cause the wing-bars 4 to assume oppositely outspread angular relationship with the centre-bar 1 in a similar manner.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. A hurlable and floatable duck-hunters' drag for landing floating, shot ducks, comprising in combination a floatable centre-bar, a pair of floatable spring-spread wing-bars for the purpose specified, hingedly secured to one end of said centre-bar, means for locking said wing-bars against outward spring-bias to the opposite end of said centre-bar, and an anchor cord connected to said locking means for releasing said wing-bars from the latter upon pulling the same so that said wing-bars assume oppositely outspread angular relationships to said centre-bar.

2. A hurlable and floatable duck-hunters' drag for landing floating, shot ducks, comprising in combination a floatable centre-bar, a pair of floatable wing-bars for the purpose specified, hingedly secured to one end of said centre-bar, drag paddles secured to the outer ends of said wing-bars, means for locking said wing-bars in

parallel contiguous relationship with said centre-bar and on either side thereof, to the opposite end of said centre-bar, and an anchor cord connected to said locking means for releasing said wing-bars from the latter upon pulling the same so that said wing-bars assume oppositely outspread angular relationships to said centre-bar.

3. A hurlable and floatable duck-hunters' drag for landing floating, shot ducks, comprising in combination a floatable centre-bar, a pair of floatable wing-bars for the purpose specified, hingedly secured to one end of said centre-bar, a coil-spring connected at its ends to one and the other of said wing-bars adjacent the locus of hinging, means for locking said wing-bars against outward spring-bias to the opposite end of said centre-bar, and an anchor cord connected to said locking means for releasing said wing-bars from the latter upon pulling the same so that said wing-bars assume oppositely outspread angular relationships to said centre-bar.

4. A hurlable and floatable duck-hunters' drag for landing floating, shot ducks, comprising in combination a floatable centre-bar, a pair of floatable spring-spread wing-bars for the purpose specified, hingedly secured to one end of said centre-bar, means for locking said wing-bars against outward spring-bias to the opposite end of said centre-bar, said locking means consisting of a casing on one end of said centre-bar, a spring-loaded shot-bolt within said casing, bolt receivers on the outer ends of said wing-bars projectable into said casing, and an anchor cord connected to said locking means for releasing said wing-bars from the latter upon pulling the same so that said wing-bars assume oppositely outspread angular relationships to said centre-bar.

5. A hurlable and floatable duck-hunters' drag for landing floating, shot ducks, comprising in combination a floatable centre-bar, a pair of floatable wing-bars for the purpose specified, hingedly secured to one end of said centre-bar, drag paddles secured to the outer ends of said wing-bars, means for locking said wing-bars in parallel contiguous relationship with said centre-bar and on either side thereof, to the opposite end of said centre-bar, said locking means consisting of a casing on one end of said centre-bar, a spring-loaded shot-bolt within said casing, bolt receivers on the outer ends of said wing-bars projectable into said casing, and an anchor cord connected to said locking means for releasing said wing-bars from the latter upon pulling the same so that said wing-bars assume oppositely outspread angular relationships to said centre-bar.
